MULTI-SERVICE MODULE FOR A MOBILE CAMPER PARK

Robert L. Smith, Minnetonka, Minn., assignor to
Roart Plastics, Inc., Hopkins, Minn.

Filed Dec. 11, 1974, Ser. No. 531,553

Term of patent 14 years

Int. Cl. D13—03

U.S. Cl. D26—12

FIG. 1

FIG. 2

FIG. 3

FIG. 4

FIG. 5

FIG. 6

FIG. 1 is a perspective view of a multi-service module for a mobile camper park showing my new design;

FIG. 2 is a side elevational view thereof;

FIG. 3 is a front elevational view thereof;

FIG. 4 is a top plan view thereof;

FIG. 5 is a rear elevational view thereof; and

FIG. 6 is an elevational view taken from the side opposite that shown in FIG. 2.

I claim:

The ornamental design for a multi-service module for a mobile camper park, as shown.
